UNITED STATES PATENT OFFICE.

VINCENT J. LAWSON, OF NEW YORK, N. Y.

CLAMP FOR HAT-PRESSING MACHINES.

SPECIFICATION forming part of Letters Patent No. 770,593, dated September 20, 1904.

Application filed June 17, 1904. Serial No. 213,025. (No model.)

To all whom it may concern:

Be it known that I, VINCENT J. LAWSON, a citizen of the United States, and a resident of the city of New York, borough of Manhattan, 5 in the county of New York and State of New York, have invented a new and Improved Clamp, of which the following is a full, clear, and exact description.

The invention relates particularly to a clamp 10 intended for use in connection with hat-pressing machines, by means of which the felt may be drawn outward from the mold in case the felt does not reach to the edges thereof.

The invention resides in certain special features of construction and arrangement of parts, which will be fully set forth hereinafter, and pointed out in the claims.

Reference is had to the accompanying drawings, showing one embodiment of my invention, 20 in which drawings like characters of reference indicate like parts in the several views, and in which—

Figure 1 is a vertical section of a hat pressing or forming machine, showing the clamps 25 in use in connection therewith. Fig. 2 is an enlarged section of the clamp, and Fig. 3 is a plan view of the same.

In Fig. 1, *a* and *b* indicate the mold-sections, and *c* the felt of which the hat is formed. The 30 present invention is employed to draw out the felt, so that its edges lie at or beyond the outer edges of the mold. In effecting this result two or more clamps are engaged with the felt, and by a strain manually applied through 35 the clamps the felt may be drawn out, as indicated in Fig. 1.

The clamp comprises two jaws 10 and 11, the latter having a groove 11^a in its upper edge, receiving the correspondingly-tapered 40 lower edge of the jaw 10, and both jaws are arc-shaped in form, as indicated in Fig. 3, causing them approximately to conform to the marginal shape of the mold. The jaws 10 and 11 are respectively carried on shanks 45 12 and 14, of which the shank 12 is provided with a recess 12^a, receiving a lug 14^a on the shank 14. The parts are pivotally joined at this point by a pin 15, and it will be observed that the swinging movement of the shanks 12 50 and 14 from each other is limited by the en-

gagement of the lug 14^a with the walls of the recess 12^a in the manner indicated by the broken lines in Fig. 2.

16 indicates a spring which is fastened to the shank 14 and bears against the under side 55 of the shank 12, this spring tending to throw the jaws from each other.

The jaws may be moved toward each other and held in clamping or active position, as shown in Figs. 1 and 2, by means of an elbow-lever 17, which is mounted to swing on a pin 18, carried in two lugs 19, which project from the jaw 11 and pass through openings 12^b in the jaw 10. The short arm of the elbow-lever 17 bears on a wear-plate 20, secured to the 65 shank 12, and the long arm of the elbow-lever is adapted to extend upward in the position shown by the dotted lines in Fig. 2, in which position the jaws 10 and 11 are separated, or to extend downward alongside of the shank 70 12, in which position the jaws 10 and 11 will be engaged together. The jaw 10 is provided with one or more horns 21, which project upward from the jaw and are adapted to engage the upper section of the mold or press, as 75 shown in Fig. 1.

In the use of the invention the felt is placed between the mold-sections in the usual manner, and in case the felt is not large enough to extend to or beyond the edges of the mold 80 85 the jaws 10 and 11 of two or more clamps are engaged with the felt and tightened together by throwing out the elbow-lever 17 in the position shown by full lines in Fig. 2. Then by engaging the horns 21 with the upper mold 85 and rocking upward the clamps the felt may be drawn out from between the mold or press sections, and thus a section of felt originally 90 too small for the mold or press may be conveniently stretched out to the desired size. 90

Various changes in the form, proportions, and minor details of my invention may be resorted to at will without departing from the spirit and scope thereof. Hence I consider myself entitled to all such variations as may 95 lie within the terms of my claims.

Having thus described my invention, I claim as new and desire to secure by Letters Patent—

1. A clamp comprising two sections each having a jaw and a shank, a pivotal connec- 100

tion between the shanks, a lug projecting from one of said sections past the other, an elbow-lever pivoted on the lug and engaging said sections, and a horn projecting from one of the jaws for the purpose specified.

5. 2. A clamp comprising two sections each having a jaw and a shank, a pivot connecting the shanks at the end opposite the jaws, a spring tending to separate the jaws, means
10 acting between the jaws to move them to-

gether, and a horn projecting laterally from one jaw for the purpose specified.

In testimony whereof I have signed my name to this specification in the presence of two subscribing witnesses.

VINCENT J. LAWSON.
